UNITED STATES PATENT OFFICE.

FRANK REICHENBACH, OF JOLIET, ILLINOIS.

HAT-PIN-POINT PROTECTOR.

1,013,814.

Specification of Letters Patent.

Patented Jan. 2, 1912.

Application filed September 6, 1911. Serial No. 647,814.

To all whom it may concern:

Be it known that I, FRANK REICHENBACH, a citizen of the United States of America, residing at Joliet, in the county of Will and 5 State of Illinois, have invented certain new and useful Improvements in Hat-Pin-Point Protectors, of which the following is a specification, reference being had therein to the accompanying drawing.

10 This invention relates to a hatpin point protector, and the primary object of my invention is to provide a device that can be easily mounted upon the pointed end of a pin to serve two purposes, namely, that of 15 locking the pin in a hat and preventing its accidental displacement, and guarding the end of the pin whereby pedestrians or other objects cannot be injured when contacting with the same.

20 A further object of this invention is to provide a combined lock and guard for a hatpin that is inexpensive to manufacture and susceptible to any desired ornamentation.

25 With the above and other objects in view, the invention resides in the novel construction, combination and arrangement of parts to be hereinafter specifically described and then claimed.

30 Reference will now be had to the drawing, wherein:—

Figure 1 is a side elevation of a pin having a guard thereon in accordance with this invention, Fig. 2 is an enlarged vertical sectional view of the guard and lock, Fig. 3 is a side elevation of a funnel-shaped mouthpiece adapted to form part of the guard and lock, Fig. 4 is a side elevation of a detached brace for the funnel-shaped mouthpiece, and Fig. 45 35 40 5 is a perspective view of a gripping member detached from the body portion whereby the free ends of the arms of the member are allowed to spring apart.

A combined lock and guard in accordance with this invention comprises a conical-shaped hollow body 1 having the lower end thereof reduced to provide an annular seat 2, said body terminating in a hollow knob 3 containing a piece of cork 4 or other yielding material. Mounted upon the seat 2

in the lower end of the body 1 is a resilient gripping member comprising oppositely disposed arms 5 and 6 with the arms 6 disposed at right angles to the arms 5 and of a less length than said arms. The lower ends 55 of said arms are formed integral with each other and the upper diverging ends of said arms are bent to provide oppositely disposed gripping teeth 7 adapted to frictionally engage the shank 8 of a hatpin placed in the 60 body 1 between the arms 5 and 6. The outer part of the body 1 engages the arms 5 and 6 so as to force them together whereby the teeth 7 will be caused to frictionally engage the shank 8 of the pin when said 65 shank is passed between the arms. The point 9 of the pin extends through a small opening 10 provided therefor at the base of the gripping member, said point extending into the piece of cork 4. 70

The upper flared end of the body 1 is provided with a funnel-shaped mouthpiece 11 to guide the shank of the pin into the body 1 and between the arms 5 and 6. The lower end of the mouthpiece 11 extends in 75 proximity to the upper ends of the arms 6 and this end of the mouthpiece is held by a horizontal brace 12 having resilient arms 13 frictionally engaging the inner walls of the body 1 and holding the brace in position, 80 whereby the mouthpiece will be concentric to the body 1. The outer edges of the funnel-shaped mouthpiece 11 are reamed upon the upper edges of the body 1, as at 14, whereby the funnel-shaped mouthpiece can- 85 not become accidentally displaced.

It is thought that the operation and utility of the device will be apparent without further description, and while in the drawing there is illustrated a preferred embodiment of the invention, it is to be understood that the device can be made of any desired material and of various sizes. 90

What I claim is:—

A hatpin protector comprising a conical-shaped hollow body having the lower end thereof reduced to provide a seat, a gripping member arranged upon said seat and having oppositely disposed arms with some of said arms of a greater length than the 100

other arms and the upper ends of said arms bent to provide teeth adapted to grip a hatpin placed in said body, a funnel-shaped mouthpiece carried by the upper end of said body, and a horizontal brace arranged in said body for the lower end of said mouthpiece.

In testimony whereof I affix my signature in the presence of two witnesses.

FRANK REICHENBACH.
